(57) **CLAIM**

The ornamental design for a tire tester, as shown and described.

DESCRIPTION

FIG. 1 is a perspective view of a tire tester showing my new design,

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 shows one application of the present invention, where those indicated by dashed lines are not claimed in the present invention.
